UNITED STATES PATENT OFFICE

HARRY H. EVANS, OF NEW YORK, N. Y., ASSIGNOR TO ADJUSTA COMPANY, OF NEW YORK, N. Y., A CORPORATION OF NEW YORK

BUCKLE SETTING DEVICE

Application filed April 29, 1931. Serial No. 533,713.

- This invention relates to a set for setting the prongs of prong-attached buckles and the like; and the immediate object thereof is to provide a simple and efficient tool for setting 5 the prongs of hook buckles, and of staples therefor, by which they are to be attached to belts, bands, etc.—for example, to the waistbands of trousers and to the waist- and/or leg-bands of knickerbockers.
10. To this end, my new setting device comprises, briefly stated, a seating member, preferably the lower member of the set, which receives and positions the buckle with its prongs and usually an end hook-piece projecting upwardly; and, cooperating therewith, a setting member provided on its opposite sides with anvil elements adapted to engage the points of the one or more prongs on each side of the buckle and to first turn them outwardly 15 wardly; and, then force them around in a loop and back to the body of the buckle, and, preferably also, at its rear end with a head adapted to set the hook-piece. In its preferred form, the upper member is further provided at its 20 forward end with means for releasably holding a staple in position with its prongs downwardly extended, and the lower member carries a cooperating anvil element adapted to engage the points of the two prongs at each 25 end of the staple and turning them inwardly towards each other, to set them. These two members are to be mounted in the usual or in any suitable manner, the upper setting member preferably as the movable member, 30 in a hand, foot, or motor operated press.
35. One practical embodiment of the invention is shown, by way of illustration and not of limitation, in the accompanying drawing, in which—
40. Figure 1 is a perspective view of the device, showing the upper member in raised position and partly in section and a buckle in position on the lower member; Fig. 2 is a view showing in perspective the lower face of the 45 upper member; Fig. 3 is a cross-sectional view of the two members and of a buckle and a band to which the buckle is to be attached; Fig. 4 is a perspective view of the end of a band to which a buckle has been attached; Fig. 5 is a view, similar to Fig. 1, showing

the forward ends of the two members and a buckle staple positioned thereon; and Fig. 6 is a perspective view of the end of a band and of the attached staple.

Referring to the drawing, the lower seating member 10, which as usual is to be set into and secured in the bed of a setting machine, has an upper face with slightly raised sides which extend from its rear end forwardly for a portion of its length and provide oppositely disposed shoulders 11 11, and, in the preferred form shown, upon these raised sides are secured narrow plates 12 12 which project inwardly slightly beyond the shoulders to form shallow grooves suitably spaced apart 60 to receive and guide the side edges of the buckles; and to the rear end of the member is secured an upwardly projecting stop 13. This member, as here shown, also has in its upper face a shallow depression 14, convex- 65 70 75 80 85 90 95 100

ly curved in section, which extends transversely thereof near its forward end and constitutes an anvil element for setting the prongs of buckle staples.

The upper setting member 15, provided with a suitable shank by which it is secured to the movable plunger of the setting machine, as usual, has in its lower face a central longitudinal recess 16 and two oppositely disposed shallow grooves 17 17, each with a gently-inclined inner and a steeply-inclined outer wall joined at the bottom by a slight concave curve, which extend from the rear end of the member forwardly for a portion of its length and constitute anvil elements for setting the prongs of the buckles. The member is also equipped, for setting the hooks of the buckles, with a setting head 18 which is adjustably mounted, within a recessed chamber 19 at the rear end of the member, by means of a threaded shank 20 passing through a threaded opening 21 and locked in adjusted position therein by a lock-nut 22. The sides of the recess 16 are cut away at 23 23, at the forward ends of the anvil elements, and again, in the narrower forward end of the member, to form shallow flat-bottomed notches 24 24 adapted to receive a staple, and, within the recess, there is mounted a spring-finger 25 which extends forwardly

therein and somewhat beyond the end of the member.

For the buckle setting operation of the device, a buckle *a*, with integral prongs *b b* and an end hook-piece *c* stamped therein and bent up at the back thereof and preferably after the buckle has been positioned upon and its prongs pressed through the end of a band *x* or other article to which it is to be attached, is placed face down on the seating member, and, its side edges entering and sliding in the guide grooves, is pushed back therein until its end, or the hook-piece at its end, abuts against the stop 18; and, when thus positioned and held and the setting member is forced downwardly, the gently-inclined inner walls of the anvil elements engage the tips of the prongs on the opposite sides of the buckle and press them outwardly and then the tips are looped over against the steep outer walls and forced down and back through the band, as shown in dotted lines in Fig. 3, thus fastening the buckle securely and permanently to the band. At the same time and by the same operation the head 18, suitably adjusted for the thickness of the band to which the buckle is attached, engages the tip of the slightly inclined hook-piece of the buckle and sets it down to form the hook at the back of the band.

To set the buckle staples, a staple *d*, with its four prongs *e e* projecting downwardly, is placed midway its length upon the extended end of the finger 25 and is pressed down on and then back along the finger to position to enter the notches 24 24 into which it is raised and there held by the finger; the end of the strap *y* to which it is to be attached, usually the other end of the same strap to which the buckle has been attached, is then positioned over the transverse anvil element of the seating member; and then, as the machine is operated and the upper member is forced downwardly, the prongs of the staple are forced through the band and are set therein, the two prongs at each end of the staple being set towards each other as shown in dotted lines in Fig. 6.

It is to be understood that certain features of the device may be used without others and that the structural details thereof may be modified, within the scope of the appended claim, without departing from the spirit or sacrificing the substantial advantages of the invention.

What I claim as new and desire to secure by Letters Patent, is—

A buckle setting device comprising, in combination, a seating member having oppositely disposed guide elements adapted to engage the sides of and to position laterally a pronged buckle with an upwardly projecting hookpiece, a stop adapted to engage the end of and to position the buckle longitudinally, and, cooperating with the said mem-

ber, a setting member having oppositely disposed anvil elements adapted to engage the tips of the upwardly projecting prongs on the sides of the buckle positioned on the seating member and to press them first to one side and then over and back to the body of the buckle, and an adjustably mounted element adapted to engage the end of the upwardly projecting hookpiece of the buckle to form the hook.
